UNITED STATES PATENT OFFICE.

CASSIUS A. BARNES, OF LOS ANGELES, CALIFORNIA.

SHADE BRACKET.

Application filed July 14, 1924. Serial No. 725,991.

To all whom it may concern:

Be it known that I, CASSIUS A. BARNES, a citizen of the United States, residing at Los Angeles, in the county of Los Angeles and State of California, have invented new and useful Improvements in Shade Brackets, of which the following is a specification.

This invention contemplates the provision of a combined window shade roller and curtain pole bracket which is formed from a single piece of material, and designed to be secured to the window casing without the use of separable fastening elements.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

25 Figure 1 is a view showing how the invention is used.

Figure 2 is a view in elevation of one of the brackets.

30 Figure 3 is a transverse sectional view through the bracket.

Figure 4 is a view taken at a right angle to Figure 1 and partly in section showing how different curtain poles are supported on the bracket.

35 Figure 5 is a plan view of Figure 4.

The invention of course includes two brackets, which are identical in construction, except that the body of one bracket is formed with an opening to receive one end 40 of the window shade roller, while the other bracket is formed with a slot to receive the other end of the window shade roller in the usual manner. One of these brackets is clearly shown in Figure 2, being formed

45 from a single piece of material and including a body portion 10 which is tapered longitudinally to terminate in a pointed extremity 11. Projecting from the lower edge of the bracket adjacent the pointed extremity 11, is a pointed prong 12, which projects

50 at a right angle from the lower edge of the bracket and therefore defines a shoulder 13 for a purpose to be hereinafter described. Formed on the upper and outer corner of

55 the body portion 10 is a substantially U-shaped member, the parallel limbs 14 of

which project an appreciable distance above the upper edge of the body 10, and is adapted to receive and support a lace curtain pole 15 of the character shown in Figures 1, 4 and 5. As clearly shown in Figure 1, this pole is of cylindrical contour and is supported by the U-shaped members of the companion brackets when the latter are mounted upon the window casing in the manner illustrated. The bracket shown in Figure 2 is provided with the slot 16 above referred to and receives the adjacent end of the window shade roller 17, the other end being received by an opening 18 formed in the other bracket 60 as shown in Figure 4. Arranged centrally of the body portion 10, and at one side thereof is an upturned portion 19 which forms an integral part of the body 10, and extended from the lower edge of said body as 65 clearly shown in Figures 2 and 3. This upturned portion has one edge stepped to provide shoulders 20 and 21 respectively for a purpose to be presently described, while the free upper end terminates to provide a 70 projection 22. This upturned portion is used in conjunction with a lace curtain pole of the configuration shown in Figures 4 and 5, and of well known construction, 75 wherein it will be noted that the pole is made of telescopic sections 23 and 24 respectively, and of U-shape design in plan. The sections are hollow and substantially of rectangular contour in cross section, and the parallel extremities 25 are adapted to be slipped over 80 the upturned portions 19 of the adjacent brackets as clearly shown in Figure 4. When the upturned portions are positioned or received within the adjacent extremities 85 25 of this pole, it bears against one of the shoulders formed by the upturned portion 19, while the projection 22 is received by an opening 26 formed in the upper edge of 90 the pole. This arrangement is clearly shown in Figure 4, and is such as to hold the pole 95 immovably mounted upon the brackets. 100

These brackets can be secured to the window casing without using nails or any other analogous fastening elements, it being only necessary to drive the pointed extremity 11 into the window casing as shown in Figures 4 and 5, and when this extremity is thus driven into the window casing it has a tendency to bend or enter the casing obliquely as 105 shown in Figure 5, which serves to prevent casual separation of the bracket from the window casing. The bracket is of course 110

driven in a sufficient distance to bring the shoulder 13 formed by the pointed prong or extension 12 into contact with the outer surface or face of the window casing, which 5 of course serves as an additional support to the bracket and the weight of the various elements which is adapted to be mounted on the bracket. The window shade roller 17 can then be easily positioned between the 10 bracket as above described, and either a round curtain pole 15 or a curtain pole of the character shown in Figure 5 used in connection with said brackets. In other words if the ordinary round pole is used, 15 it is arranged within the U-shaped portions of the bracket, while on the other hand if a flat curtain pole is used, the extremities thereof are slipped over the upturned portions 19 as above described. The bracket 20 being formed from a single piece of material and by reason of its simplicity, can be manufactured and sold at a very small cost.

While it is believed that from the foregoing description, the nature and advantages 25 of the invention will be readily apparent, I desire to have it understood that I do not limit myself to what is herein shown and described, and that such changes may be resorted to when desired as fall within the 30 scope of what is claimed.

What I claim is:

1. A bracket of the character described comprising a body portion having an opening therein, a U-shaped member projecting 35 upwardly from the upper edge of said body and at one corner thereof, and an upturned extension projecting from the lower edge of the body and arranged at one side and in spaced parallel relation with said body 40 for the purpose specified.

2. A bracket of the character described comprising a body portion having an opening therein, a U-shaped member rising from 45 the upper edge of the bracket at one corner thereof, an upturned portion arranged centrally of the bracket and at one side thereof, said upturned portion being connected with

the lower edge of the bracket, shoulders formed on one edge of the upturned portion, and a pointed projection extending 50 from the free end of said upturned portion for the purpose specified.

3. A bracket of the character described comprising a body portion having an opening, and terminating to provide a pointed 55 extremity, a pointed prong depending from the lower edge of the bracket adjacent the pointed extremity, a U-shaped member rising from the upper edge of the bracket adjacent the other end thereof, an upturned 60 portion projecting from the lower edge of the bracket and arranged at one side and approximately centrally of said bracket, shoulders formed on one edge of the upturned portion, and a projection extending 65 from the free end of said upturned portion for the purpose specified.

4. A window bracket of the character described comprising a body portion tapered toward one end to provide a pointed extremity adapted to be driven into the window casing, a pointed prong depending at a right angle from the lower edge of the bracket and defining a shoulder adapted to bear against the window casing when the 70 bracket is driven thereinto, a U-shaped member rising from the upper edge of the bracket at the opposite end thereof and adapted to receive a curtain pole, an upturned extremity projecting from the lower edge of the bracket and arranged at one side thereof and adapted to be received by a hollow curtain rod of well known construction, a shoulder formed on the outer edge of the upturned portion and adapted to be engaged by the adjacent end of said rod, and a projection extending from the 75 free end of the upturned portion and adapted to be received by an opening in said rod as and for the purpose specified. 80

In testimony whereof I affix my signature.

CASSIUS A. BARNES.
